UNITED STATES PATENT OFFICE.

CLARENCE T. McDONALD, OF CHICAGO, ILLINOIS, ASSIGNOR TO CHICAGO FUSE MFG. CO., OF CHICAGO, ILLINOIS, A CORPORATION OF ILLINOIS.

REFILLABLE CARTRIDGE FUSE.

Application filed February 28, 1918. Serial No. 219,597.

To all whom it may concern:

Be it known that I, CLARENCE T. McDONALD, a citizen of the United States, residing at Chicago, in the county of Cook and State 5 of Illinois, have invented certain new and useful Improvements in Refillable Cartridge Fuses, of which the following is a specification.

The invention relates to cartridge fuses of 10 the type generally known as refillable fuses in which the fuse element or link may be readily replaced by the user when disrupted or "blown"; and the objects of the invention are to improve the construction of fuses 15 of this character; to provide a fuse which will prevent the melted metal of the fuse element from clogging or interfering with the fuse-supporting means or the clamping means; which comprises separable comple- 20 mentary parts forming between them an opening to receive the fuse element so that said opening will always be accessible for removing and replacing said element; by which an invariable position of the fuse element in the shell will be insured; and which will prevent twisting of the fuse element when the threaded clamping element is turned up against the end thereof; and to produce a fuse which is very durable, simple 25 and convenient to refill.

The objects of the invention thus generally stated, together with other and ancillary advantages, may be attained by the construction and arrangement illustrated in the accompanying drawings forming part hereof, in which Fig. 1 is a perspective view of one 35 form of fuse embodying my invention, one end of the fuse being disassembled to show the relation of parts. Fig. 2 is a fragmental axial sectional view of the same form of fuse. Fig. 3 is a transverse section on line 40 3—3 of Fig. 2. Fig. 4 is a fragmental axial sectional view through one end of a somewhat different form of fuse embodying my invention. Fig. 5 is a transverse section on line 45 5—5 of Fig. 4. Figs 6 and 7 are respectively side and edge elevations of an alternative form of disk.

The fuse comprises a casing formed by 50 means of a tubular shell 1 and metallic end members or heads 2 fixed thereon and partially closing the ends of the casing; metallic plates or segmental disks 3 which form together with the heads 2 complete closures 55 for the ends of the casing except for an elon-

gated opening formed between each end member and its corresponding disk; a fuse link 4 extending through the casing with its ends passing through the openings at opposite ends of the casing; and caps 5 or plugs 60 5' for clamping the ends of the fuse link in position upon the outer surfaces of the segmental disks.

The shell 1 of the casing is made of the usual insulating material, and each of the 65 heads 2 comprises an annular portion 2^a which is threaded or otherwise firmly secured upon one end of said shell, and a segmental wall or web portion 2^b for partially closing the end of the casing. Said segmental webs 70 at opposite ends of the casing extend transversely of the annular portions 2^a inwardly toward the centers thereof, and the inner edges are formed straight and may, if desired, be disposed in the same longitudinal 75 plane near the diametrical center of the casing.

The segmental disks 3 or 3' which are arranged to complement or cooperate with the segmental webs 2^b of the heads 2 to close 80 the ends of the casing are also formed with a straight inner edge and are made of such size that the edges form, together with the edges of the webs 2^b, straight-edged openings 6 so that the ends of the fuse link may 85 be passed therethrough and bent over upon the outer surfaces of the disks. The bent-over ends of the fuse link thus serve to hold the disks in position until the parts can be finally clamped together by means of the 90 end caps 5 or plugs 5'.

As shown in Figs. 1 to 3, the caps 5 are of ordinary construction having peripheral flanges or skirts arranged to be externally threaded upon the heads 2, the annular portions 2^a of said heads being reduced at their outer ends so that the peripheries of the heads and caps are flush. In this form of fuse, the disks 3 rest upon the outer ends of the heads 2, and, in order to form the openings 6 of sufficient length only to receive the fuse link, the disks are provided at each end of their straight edges with projections or ears 7 which are arranged to overlie the adjacent portions of the segmental webs 2^b at 105 the opposite edges of the fuse link.

The disks may also be provided near their edges with a plurality of projections or bosses 8 arranged to engage with the edges of the openings in the heads 2 to prevent ro- 110

tation of the disks with reference to the casing, or if desired each disk may be provided with an inturned flange 11 (Figs. 6 and 7) to overlap the edge of the web 2^b, and 5 with a boss 8 near the opposite edge of the disk. When the ends of a fuse link have been bent upon the outer surfaces of the disks and the end caps tightened upon the heads 2, the parts will have been firmly 10 clamped together with the fuse ends in direct electrical contact with the heads and caps. The bosses 8 and flange 11 prevent rotation, or displacement of the disks so that no twisting or distortion of the fuse can 15 occur.

In the form of fuse shown in Figs. 4 and 5, the web portion 2^b of each head 2 is spaced within the end of the annular portion 2^a thereof which is internally threaded to receive 20 the screw-threaded plug 5', the plug being provided with a groove 9 for the reception of a screw driver. In forming the web portion 2^b of this type of fuse, the straight edge of the web which forms one 25 wall of the elongated opening 6' for each end of the fuse link is made somewhat shorter than the corresponding interior dimension of the annular portion of the head, and an arcuate flange or supporting ledge 30 10 for the outer edges of the segmental disk 3' is provided upon the inner periphery of the annular portion of the head 2, extending from one end of the web 2^b to the other. The portions of the ledge 10 at the ends of 35 the web thus serve to restrict the opening 6' to a length corresponding to the width of the fuse link, and also to provide a shoulder for the disk to bear against.

In some of the fuses of the prior art, the 40 fuse element is supported at each end by a circular washer having a slot running inwardly from its periphery to receive one end of said fuse element, and this washer is clamped directly against the end of the insulating sleeve (such as is here shown at 1) by means of a metallic cap which is threaded 45 directly onto said insulating sleeve, there being no metallic head (such as is here shown at 2.) A fuse constructed in accordance 50 with my invention has many inherent advantages over such prior constructions. In the manufacture of the fuse, the metallic heads 2 may be permanently fixed on the ends of the insulating sleeve 1 so that the 55 webs 2^b of said heads will be in invariable position which will not be altered by the user in refilling the fuse. Perfect positioning of the fuse is thus always insured. The threads to receive the clamping member 5 60 or 5' which is removed and replaced at every fuse renewal are in the metallic head instead of in the insulating sleeve. This sleeve is usually made of fibrous material and the threads therein are more or less easily worn 65 out and cut by the repeated removal and

replacement of the cap. The threads may even wear down to such an extent that the cap is insecurely held on the sleeve so that it is dangerous when the fuse blows because the high pressure in the fuse may blow the 70 cap off and injure a bystander.

By providing the webbed heads 2 which are permanently fixed on the sleeve, the disks 3-3' are held in definite position by reason of the abutting relation of the disks 75 or the fuse element to the webs, so that no twisting of the fuse element can be caused by the frictional engagement of the cap 5 or plug 5' when the cap or plug is being turned up against the fuse end. Furthermore, the 80 ends of the fuse are firmly clamped between metallic faces so that shrinkage or variation of the fibre tube 1 will have no effect, and good electrical contact between the fuse element and terminal parts is always in- 85 sured.

With some of the fuses heretofore known difficulty has been experienced on account of the fact that when the fuse element is disrupted the melted part thereof within the 90 shell is forced outward by the pressure, and passing through the openings in the end-closing means becomes lodged in such openings and in the screw threads for the clamping cap or the like and interferes with the 95 operation of the parts. In the type of washer which has a slot running inward from its periphery to receive the fuse element, it has been found difficult oftentimes to remove the fuse element from the washer 100 after it blows and to insert a new fuse element on account of the plugging or clogging of the slot by the melted metal. In some instances the nuisance of removing and replacing the fuse element has been so great 105 that the user would intentionally break off a portion of the washer at one side of the slot so as to provide a more readily accessible support for the fuse. After such piece of the washer was broken off, the washer 110 fell short of completely closing the end of the shell so that at the next disruption of the fuse the melted metal would escape in greater quantities through the larger sized opening and clog the threads of the cap and 115 other parts to a greater extent.

My construction entirely eliminates these difficulties by preventing the melted fuse material from getting through the opening which the strip occupies and by nullifying 120 any bad effect of the melted metal adhering to the inner sides of the end closing means or partially entering the slots through which the fuse element passes. A washer having a flange 11, as shown in Figs. 6 and 7, is especially effective for this purpose because it provides (in conjunction with the web 2^b) a slot of considerable depth. By reason of the fact that the web 2^b is integral with the head 2 and the slot for the fuse is formed 130

between such web and the separate disk, a fuse-receiving slot is provided which opens up when the disk is removed so that it is always easy to remove the blown fuse element 5 from the slot and replace a new fuse element therein. Furthermore, the provision of the segmental web on the head and the complementary segmental washer separate therefrom has the advantage of forming a slot 10 which has straight edges at both sides so that the fuse element snugly fits the slot and prevents any melted metal from escaping from the interior of the shell.

As will be noted from an inspection of 15 Figs. 3 and 5 the slot defined by the opposed straight edges of the web 2^b and disk 3 or 3' occupies the relation of a chord to a circle defined by the periphery of the head 2. Preferably the disk 3 or 3' comprises the 20 larger segment of such circle and the web 2^b the smaller segment so that when the disk is removed for renewal of the fusible element, a relatively large opening will be left through which the new fusible element may 25 be readily inserted without any danger of bending or cracking the element which might affect its calibration. When the fusible element has been inserted through both heads the disk 3 or 3' may be very easily put 30 in place to close the remainder of the opening through the head.

I claim as my invention:

1. A refillable cartridge fuse having, in combination, a tubular insulating shell, a 35 rigid one-piece tubular metallic head fixed to one end of said shell and having screw threads to receive a clamping member, a clamping member threaded to removably engage the threads of said head and having a 40 clamping wall perpendicular to the axis of said head, a freely removable disk at the inner side of and parallel to said clamping wall, said disk being arranged to abut at one side against a rigid integral part of said 45 head, a fusible strip in said shell having one end bent to extend between said disk and said clamping wall, whereby when the clamping member is turned up the end of the fusible strip will be clamped between 50 said clamping wall and said disk, and the disk will be forced against said rigid part of the head, and an inwardly projecting web integral with said head lying in a plane parallel to said disk and clamping wall and 55 having a straight inner edge, said disk having a complementary straight edge positioned close to and coacting with said straight edge on the web to form a narrow slot through which said fusible strip extends with a relatively snug fit.

2. A refillable cartridge fuse having, in combination, a tubular insulating shell, a one-piece rigid metallic head fixed to one end of said shell and having a large opening 60 through which a fusible element may be in-

serted, a flat strip fusible element, means for closing said opening including two separable parts one of which is integral with said head and the other of which is freely removable, said two parts being arranged in 70 juxtaposition and having opposed straight edges defining a narrow slot through which said fuse element extends with a relatively snug fit, and a clamping element having a threaded engagement with said head and arranged to clamp the end of said fusible element and said removable part.

3. A refillable cartridge fuse having, in combination, a tubular insulating shell, a metallic head fixed to one end of said shell 80 and being threaded at its free ends to receive a clamping member, a clamping member threaded to engage said head, said head having an opening therethrough with a straight-edged wall defining one side of the 85 opening, a flat fuse strip passing through said shell and the opening in said head and lying adjacent to the straight-edged wall, and a freely removable transverse disk arranged to close said opening and having a 90 straight edge positioned adjacent to the straight edge of said wall to define a narrow slot through which the fuse strip passes, the end of said fuse strip being clamped between said clamping member and said disk, 95 said disk having a plurality of bosses projecting from its inner face and arranged to cooperate with the head to prevent relative rotation of the disk and the head.

4. A refillable cartridge fuse having, in combination, a tubular insulating shell, a one-piece tubular rigid metallic head fixed to one end of said shell and having screw threads to receive a clamping member, a 100 readily removable clamping member threaded to engage the threads of said head and having a clamping wall perpendicular to the axis of said head, an internally projecting transverse web integral with said head and having a straight inner edge, said web partially closing the passage through said head but leaving a relatively large opening through which a fusible strip may be readily inserted in assembling the fuse, a freely 105 removable disk lying between and parallel to the planes of said web and the clamping wall of said clamping member, and a fusible strip in said shell having one end bent at an angle to extend between said disk and said clamping wall to be clamped thereby, 110 said disk abutting at its other side against a rigid integral part of the head, and said disk having a straight edge which coacts with the straight edge of said web to define a narrow slot through which said fusible 115 strip extends with a relatively snug fit.

5. A refillable cartridge fuse having, in combination, a tubular insulating shell with an exteriorly threaded end, a one-piece tubular metallic head interiorly threaded at 120 125

one end to fit the threaded end of the shell and also exteriorly threaded and reduced in diameter at its other end, a removable cap having a peripheral flange internally 5 threaded to receive the reduced end of said head, the peripheries of the cap and head being flush with each other, a freely removable disk at the inner side of said cap and abutting against the outer end face of said 10 head, said disk having a straight edge, a fusible element extending through said shell and having one end bent at an angle to extend between the end wall of said cap and the said disk and be clamped thereby, and 15 a transverse web integral with said head and lying in a plane flush with the outer end of said head and immediately adjacent to said disk, said web having a straight inner edge which coacts with the straight edge 20 of said disk to form a narrow slot through which said fusible element passes with a relatively snug fit.

6. A refillable cartridge fuse having, in combination, a tubular insulating shell, a 25 one-piece rigid tubular metallic head fixed to one end of the shell and threaded to engage with a clamping member, a threaded clamping member adapted to removably engage the said head, a freely removable trans- 30 verse disk positioned at the inner side of said clamping member and abutting against a rigid integral part of said head, said disk having a straight edge, and a fusible element extending through said shell and having 35 one end bent over said straight edge to extend between said clamping member and said disk and be clamped thereby, said head having a transverse wall integral therewith lying in a plane parallel and immediately 40 adjacent to the inner side of said disk, said wall having a straight edge which coacts with the straight edge of said disk to form a narrow slot through which said fusible element passes.

45 7. A refillable cartridge fuse having, in combination, a casing having a transverse web portion partially closing one end, a disk, a fuse element having one end passing between said web portion and said disk, said 50 disk having means projecting longitudinally into the casing and serving to prevent relative rotation of the disk, and means for clamping the parts together.

8. A refillable cartridge fuse having, in 55 combination, a tubular insulating shell, a one-piece tubular metallic head fixed to one end of said shell and having at its extreme outer end an integral transverse internally projecting web with a straight edge, a re- 60 movable disk having a straight edge and arranged to coat with said web to form a narrow slot, a flat fusible strip passing through said slot and having one end bent over the straight edge of the disk to lie along 65 the outer face of the disk, and a cap having

a skirt in threaded engagement with said head to clamp said strip and said disk to the head.

9. A refillable cartridge fuse having, in combination, a tubular insulating shell, a 70 one-piece tubular metallic head fixed to one end of said shell and exteriorly threaded, a removable cap having a peripheral flange interiorly threaded to engage said head, a 75 freely removable disk at the inner side of said cap and abutting against the outer end face of said head, said disk having a straight edge, a fusible element in said shell having one end bent over said straight edge to extend between said cap and said disk and 80 be clamped thereby, and a transverse web integral with said head and lying in a plane flush with the outer end of said head immediately adjacent to said disk, said web having a straight edge which coacts with the 85 straight edge of said disk to form a narrow slot through which said fusible element passes with a relatively snug fit.

10. In a refillable cartridge fuse a tubular body having a metallic head provided with 90 an integral inwardly extending portion, a fuse element, and a member having means projecting longitudinally into the head and arranged to co-operate with said inwardly extending portion of the head to position the fuse element relative thereto.

11. In a refillable cartridge fuse a tubular body having a metallic head provided with an integral inwardly extending web, a fuse element, and a disk having a part project- 100 ing longitudinally into the head and forming in conjunction with the web a slot of substantial depth for receiving said fuse element.

12. In a refillable cartridge fuse, a cas- 105 ing, means partially closing one end of the casing, a fuse element, and a disk having a part projecting longitudinally into the casing between which part and said means the fuse element passes, said disk and fuse 110 element serving to completely close the opening left by said means.

13. A refillable cartridge fuse having, in combination, a tubular insulating shell, a one-piece tubular metallic head fixed to one 115 end of said shell and exteriorly threaded, a removable cap having a peripheral flange interiorly threaded to engage the threaded portion of said head, the head having at its extreme outer end an integral transverse 120 internally-projecting web with a straight edge partially closing the opening through said head, a freely removable disk abutting against said outer end of the head and having a straight edge which coacts with the 125 straight edge on said web to form a narrow slot, means to prevent relative rotation of the disk and head, and a fusible strip in the shell passing through said slot and having one end bent to lie between said disk

and the end wall of said cap, whereby the strip will be clamped between the disk and the cap, and the disk will be clamped against the head.

5 14. In a refillable cartridge fuse, in combination, a casing, a one-piece tubular metallic head threaded on the end of said casing, an integral inwardly projecting transverse web on said tubular head, a removable disk, adjacent to said web and co-operating therewith to form a complete closure for the end of said casing, except for a narrow straight slot, a fuse element passing through said slot and having its end portion overlying said disk, said disk having a projection cooperating with said head to prevent relative rotation of the disk and head, and clamping means engaging the metal of said tubular head for clamping the 10 end of said fuse element and said disk.

15 15. In a refillable cartridge fuse, in combination, a tubular head, an integral inwardly projecting transverse web on said head, a removable disk cooperating with said web to define a narrow straight slot between their adjacent edges, means to prevent relative rotation of the disk and head, a fuse element passing through said slot and having its end portion overlying said 20 disk, and means engaging said tubular head for clamping said disk and fuse element.

16. A refillable cartridge fuse having, in combination, a tubular insulating shell having a threaded end, a one-piece tubular metallic head having a screw-threaded engagement with the shell and also threaded to engage with a clamping member, a threaded clamping member adapted removably to engage the said head, a freely removable 25 disk positioned transversely at the inner side of said clamping member and having a straight edge, and a fusible element extending through said shell and having one end bent at an angle over the straight edge of the disk to extend between said clamping members and said disk and be clamped thereby.

30 17. A refillable cartridge fuse having, in combination, a tubular insulating shell having a threaded end, a one-piece tubular metallic head having a screw-threaded engagement with the shell and also threaded to engage with a clamping member, a threaded clamping member adapted removably to engage the said head, a freely removable 35 disk positioned transversely at the inner side of said clamping member and having a straight edge, and a fusible element extending through said shell and having one end bent at an angle over the straight edge of the disk to extend between said clamping members and said disk and be clamped thereby.

40 18. A refillable cartridge fuse having, in combination, a tubular insulating shell having a threaded end, a one-piece tubular metallic head having a screw-threaded engagement with the shell and also threaded to engage with a clamping member, a threaded clamping member adapted removably to engage the said head, a freely removable 45 disk positioned transversely at the inner side of said clamping member and having a straight edge, and a fusible element extending through said shell and having one end bent at an angle over the straight edge of the disk to extend between said clamping members and said disk and be clamped thereby.

50 19. In testimony whereof, I have hereunto set my hand.

CLARENCE T. McDONALD.
